(**) Term: **14 Years**

(57) **CLAIM**

(21) Appl. No.: **29/325,371**

The ornamental design for a self-contained biological indicator, as shown and described.

(22) Filed: **Sep. 30, 2008**

DESCRIPTION

(51) **LOC (9) Cl.** 24-02

FIG. 1 is a perspective view of a self-contained biological indicator showing our new design;

(52) **U.S. Cl.** **D24/224**

FIG. 2 is a side elevation view of FIG. 1;

(58) **Field of Classification Search** D24/216,

FIG. 3 is a top plan view of FIG. 1;

D24/224, 227; 422/50, 102, 99
See application file for complete search history.

FIG. 4 is a bottom plan view of FIG. 1;

(56) **References Cited**

FIG. 5 is a first side elevation view of the container body of the self-contained biological indicator (with the cap detached therefrom);

U.S. PATENT DOCUMENTS

FIG. 6 is a second side elevation view of container body of the self-contained biological indicator (with the cap detached therefrom);

FIG. 7 is a top plan view of FIG. 5
